UNITED STATES PATENT OFFICE.

JOSHUA MOORE, OF MARSEILLES, ILLINOIS.

ROAD-GRADING MACHINE.

SPECIFICATION forming part of Letters Patent No. 374,691, dated December 13, 1887.

Application filed March 17, 1887. Serial No. 231,259. (No model.)

To all whom it may concern:

Be it known that I, JOSHUA MOORE, a citizen of the United States, residing in Marseilles, in the county of La Salle and State of Illinois, have invented a new and useful Improvement in Road-Grading Machines, of which the following is a specification.

This invention is designed to give increased strength and convenience of operation to road-grading machines of the class shown in the patent to me, No. 345,315, of July 13, 1886.

In the accompanying drawings, which form a part of this specification, and in which similar letters of reference indicate like parts, Figure 1 is a perspective view of my improved grader. Fig. 2 is a plan of the machine. Fig. 3 is a vertical section of the fifth-wheel on the line 3 3 of Fig. 2. Fig. 4 is a plan of the axle and the pole at their junction. Fig. 5 is a section on line 5 5 of Fig. 4. Fig. 6 is a cross-section of the axle, showing also a side view of the pole attachment. Fig. 7 is a section on the line 7 7 of Fig. 2. Fig. 8 illustrates the manner of connecting the hand-lever with the front end of the scraper; and Fig. 9 is a plan of the rear end of the beams, showing the manner of bracing the scraper. All the figures after Fig. 2 are considerably enlarged.

In the drawings, A A' represent the two arched beams extending from the front axle to the rear of the machine. They are connected by a suitable number of cross-braces, a, and at the front by the head a'. I am aware that these beams have each been made in one piece; but I prefer to make the two beams, together with their cross-connections, in one integral or homogeneous piece. This may be done by casting them together at one operation. The cross-braces may, however, if preferred, be previously formed and cast into the stock of the beams at either end of the braces in the usual manner of casting around the ends of bolts, &c. The head a' is not necessarily integral with the beams, though I prefer to make it so. The frame thus constituted of the beams and braces in one casting possesses very great rigidity and strength, and enables me to dispense with the cross rear axle shown in my former patent, as the beams possess sufficient strength to give separate stub-axles attached to them all necessary firmness.

B B are the rear wheels, and they are mounted, as already intimated, upon stub-axles b b', which stand out from attaching-plates b², secured to the beams by upper and lower longitudinal flanges, b³ and b⁴, the former of which flanges receives bolts b⁵, passing through lateral flanges b⁶ upon the beams.

While I have shown the manner of attaching the axles, I do not wish to be limited thereto, as it is obvious they can be secured in many other ways.

The scraper I is braced, as more particularly shown in Fig. 9, by brace C, extending from the front end of the forward stub-axle b, by brace C' from near the center of the board to the side beam A, by brace C² from the rear end of the board to the same beam, and by a brace, C³, to the side beam A'. Other additional braces may be employed, if desired.

The fifth-wheel of the grader is exceedingly simple and very strong, and is constructed as follows: I recess the under side of the head a' with a straight round opening, d, and insert therein a boss, D, formed upon the plate D', which rests upon and is bolted to the axle E of the front wheels, E'. The boss D is tapering, so that room is afforded in the upper part of the opening d to permit the rocking of the axle. The king-bolt d' passes through the head a', the boss, the plate, and the axle, as clearly shown in Fig. 3, and the openings in those parts afford it freedom in the various movements of the axle, as clearly shown in said figure. The pole F is attached to the axle by means of the forwardly-projecting flanged casting F', which is preferably formed in one piece with the boss D and its plate D', so that the same bolts which attach the latter to the axle serve, also, to attach the casting F'. The pole is inserted in this flanged casting F' and secured by bolts f. This construction renders the union very rigid and strong and enables me to dispense with the truss arrangement shown in my former patent.

In my former machine the hand-lever for elevating the front end of the scraper-board was located at quite a remove from the driver's seat, so that it was inconvenient to operate. I now locate said lever, which is shown at G in my present drawings, in close proximity to the driver's seat G', and connect it to the scraper-

board by a rod, g , and an elbow-lever, g' , as shown in Fig. 8. The other hand-lever, H , is connected to the scraper substantially in the manner shown in my former patent, and, as it is also located within easy reach of the driver, he is enabled to operate both levers simultaneously without bending forward. The rear lip, d^3 , takes considerable strain from the attaching-bolts by which the boss and its plate are secured to the front axle.

I claim—

1. In a road-grading machine, the combination, with the arched beams and their cross-braces, of the rear wheels mounted upon stub-
15 axles rigidly attached to said beams, substantially as specified.
2. In a road-grading machine, the combination, with the arched beams, their cross-braces, and the stub-axle b , of the scraper-board and
20 the braces C , C' , C^2 , and C^3 , extending from the board to said axle and beams, respectively, substantially as specified.

3. In a road-grading machine, the combination, with the beams and their recessed head a' , the axle, and the tapering boss borne on 25 the axle, of the king-bolt passing through the head, axle, and boss, and having freedom therein to permit the rocking movements of the axle, substantially as set forth.

4. In a road-grading machine, the combination, with the pole and front axle, of a forwardly-projecting flanged casting, F' , secured to the axle and receiving the pole, substantially as specified.

5. In a road-grading machine, the pole and 35 its forwardly-projecting attaching-casting F' , in combination with the front axle and the boss-plate attached to said axle, said casting and plate being formed in one piece, substantially as specified.

JOSHUA MOORE.
